US00D749232S

(12) **United States Design Patent**
Baumwald et al.

(10) **Patent No.:** **US D749,232 S**
(45) **Date of Patent:** **** Feb. 9, 2016**

(54) **THERMAL PACK**

(71) Applicants: **Daniel Jared Baumwald**, Elkridge, MD (US); **Carol Baltazar**, Glenwood, MD (US)

(72) Inventors: **Daniel Jared Baumwald**, Elkridge, MD (US); **Carol Baltazar**, Glenwood, MD (US)

(73) Assignee: **TheraPearl, LLC**, Columbia, MD (US)

(**) Term: **14 Years**

(21) Appl. No.: **29/433,566**

(22) Filed: **Oct. 1, 2012**

Related U.S. Application Data

(63) Continuation-in-part of application No. 29/406,624, filed on Nov. 16, 2011, now Pat. No. Des. 668,344, and a continuation-in-part of application No. 12/794,576, filed on Jun. 4, 2010.

(57) **CLAIM**

The ornamental design for a thermal pack, as substantially shown and described.

DESCRIPTION

FIG. 1 is a perspective view of a thermal pack showing the new design.

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

Structure illustrated in broken lines is provided to illustrate the environment of the invention but is not otherwise part of the claimed design.

1 Claim, 4 Drawing Sheets
